[57] CLAIM

The ornamental design for combined amusement play area and an enclosing structure, as shown and described.

DESCRIPTION

FIG. 1 is a perspective view of combined amusement play area and an enclosing structure showing my new design;

FIG. 2 is a top plan view thereof;

FIG. 3 is a front elevation view thereof;

FIG. 4 is a rear elevation view thereof; and,

FIG. 5 is a right side view thereof that is a mirror image of the left side view.

FIGS. (2-5 inclusive) are drawn in an enlarged scale for clarity of illustration.

FIG. 1

FIG. 5

FIG. 2

FIG. 3

FIG. 4
